UNITED STATES PATENT OFFICE.

AUGUSTUS C. HAMLIN, OF BANGOR, MAINE.

IMPROVEMENT IN LININGS FOR FURNACES, SAFES, &c.

Specification forming part of Letters Patent No. 125,951, dated April 23, 1872.

Specification describing a new and Improved Furnace and Safe Lining Heat-Resistant, &c., invented by AUGUSTUS C. HAMLIN, of Bangor, in the county of Penobscot and State of Maine.

This invention consists in the application of itacolumite as a lining for safes, furnaces, tuyeres, to the manufacture of crucibles, and similar uses where its heat-resisting quality can be utilized.

The material named is a laminated granular quartz-rock, consisting mainly of quartz-sand, but containing a little talc, and possessing a degree of flexibility when in the lamina. It is, at present, mostly found in the States of North Carolina, South Carolina, and Georgia. Its flexibility allows it to be easily worked into the lining or heat-resisting articles specified, and permits thus the direct and inexpensive application to practical purposes of the valuable properties of quartz and quartzite.

The peculiarity of construction or composition of the itacolumite permits the expansion and contraction of heat and cold without destruction, and the material is therefore admirably adapted to all operations where the action of heat is to be resisted. It may be separated into thin sheets or thick slabs, and may also be pulverized and molded into crucibles.

Having thus described my invention, I claim as new and desire to secure by Letters Patent—

The safe and furnace lining crucible and other heat-resistants, made of the material herein specified.

AUGUSTUS CHOATE HAMLIN.
